Patented Sept. 4, 1917.

UNITED STATES PATENT OFFICE.

CHARLES MARVIN BROYLES, OF WONDER, NEVADA, ASSIGNOR OF ONE-HALF TO VAN EASTLAND, OF CHATTANOOGA, TENNESSEE.

WRENCH.

1,239,156.

Specification of Letters Patent. Patented Sept. 4, 1917.

Application filed January 8, 1917. Serial No. 141,212.

To all whom it may concern:

Be it known that I, CHARLES M. BROYLES, a citizen of the United States, residing at Wonder, in the county of Churchill, State of Nevada, have invented certain new and useful Improvements in Wrenches, and I do hereby declare the following to be a full, clear, and exact description of the invention, such as will enable others skilled in the art 10 to which it appertains to make and use the same.

This invention relates to wrenches and more particularly to improvements in quick action wrenches.

15 The object of the invention is to provide an improved form of quick action wrench in which one of the jaws, for a preliminary or rough setting is released from the second jaw and moved along the shank of the latter, and after reengagement therewith is adjustable by means of a screw device. In this connection, I mount the movable jaw slidably and pivotally upon a frame or casing which surrounds the shank of the fixed jaw, 20 and provide a relative adjustment between the frame or casing and the movable jaw so that after the casing has been set with relation to the shank to give the preliminary setting, the movable jaw may then be set up 25 with relation to the casing to take the final hold upon the element to be gripped.

With the above objects in view and such others as may hereinafter appear, my invention will now be fully set forth and described, reference being had to the accompanying drawings.

In the drawings:—

Figure 1 is a side elevation of the wrench, Fig. 2 is a side elevation with a side of 30 the frame or casing removed,

Fig. 3 is a section on line 3—3 of Fig. 2,

Fig. 4 is a section on line 4—4 of Fig. 2, and

Fig. 5 is a section on line 5—5 of Fig. 2.

45 Referring more particularly to the drawings, 1 represents the fixed jaw of the wrench which is carried upon the front end of the squared shank 2. Slidable upon the upper face of the shank 2 is a movable jaw 3 which has the casing 4 surrounding the shank 2 and the rearwardly extending body 5 which slides upon the upper face of the shank 2. Surrounding the shank 2 is a casing or frame 6 whose sides slidably 50 embrace the side of the shank 2, but which is

free to move up and down upon the latter to a limited extent so that the teeth 7 formed upon the inner face of the body of the frame 6 may be carried into and out of engagement with the teeth 8 formed along 60 the lower side of the shank 2. The teeth 8 are of such formation that the frame may be slid forwardly thereover, but may not be carried backwardly without disengaging the teeth 7 from the teeth 8. Above the 65 shank 2, the casing 6 is hollow and is provided with a pair of forwardly extending arms 9 which closely embrace the body 5, and are longitudinally slotted as at 10 to engage over headed projections or screws 70 11 extending from opposite sides of the body 5. By reason of the pivotal and slotted connection between the body 5 and the frame 6, the latter may be moved longitudinally relative to the body, and may also 75 rock upon the pins 11. Practically, throughout its length, the body 5 is provided with a longitudinally threaded bore 12 into which is threaded an adjusting stem 13 which extends thence rearwardly through the casing 80 6, and overlies the shank 2 and extends through the handle 14 in which it may have a bearing. The rear end of the stem 13 is provided with a cross head 15 by means of 85 which it may be adjusted. Within the casing 6, the stem 13 is provided with a spring 90 16 which has an intermediate portion surrounding the stem 13 and terminates at opposite sides of the latter in coiled spring arms 17 which extend upwardly into resilient contact with the top of the casing 6. The tendency of the spring 16 is to press the teeth 7 into engagement with the teeth 8.

The spring 16 is held in position between 95 a pin 18 which extends transversely through the stem 13 and a stop nut 19 which bears against the rear wall of the casing 6 and co-operates with an external pin 20 to prevent relative longitudinal movement of the stem 13 and the casing 6. It will be noted that the stem 13 in extending through the rear wall of the frame 6 passes through a vertically elongated slot 21, so that the casing 6 may have the necessary freedom with 105 relation to the shank 2 in order to free the teeth 7 from the teeth 8.

In operation, in order to engage the movable jaw 3 with the nut or other object to be engaged, the casing 6 is rocked on the 110

jaw 3 downwardly in order to disengage the teeth 7 from the teeth 8, or the casing may be slid forwardly from the shank 2 along the teeth 7 to ride past the teeth 8 until the approximate adjustment has been secured. The teeth 7 and 8 having then been reengaged, the stem 13 is turned by means of the hand grip or cross head 15 in order to move the jaw 3 forward relative to the casing 6 into tight engagement with the object. By means of the relative movement of the jaw 3 and the casing 6, a relative effective movement of approximately an inch will be secured, even without any preliminary disengagement of the teeth 7 and 8. The handle 14 provides a suitable bearing for the stem 13 so that the latter will not have any relative movement with relation to the shank 2, or any locking movement of the casing 6 cannot by any cause be communicated to the movable jaw 3 or the body 5.

What I claim as my invention is:—

1. A wrench comprising in combination, a fixed jaw and a shank, a movable jaw 25 slidable upon the shank, a casing surrounding the shank and having a pivotal and

slotted connection with the movable jaw, corresponding teeth on the shank and the casing for locking the latter in adjusted position upon the shank, and a stem threaded into the movable jaw, and having a rotary bearing in the casing, whereby an adjustment of the movable jaw relative to the casing may be effected.

2. A wrench comprising in combination, a fixed jaw and a shank, a movable jaw 30 slidable upon the shank, a casing surrounding the shank and having a pivotal and slotted connection with the movable jaw, corresponding teeth on the shank and the casing for locking the latter in adjusted position upon the shank, a stem threaded into the movable jaw and having a rotary bearing in the casing, whereby an adjustment of the movable jaw relative to the casing may be effected, a handle surrounding the shank, and a bearing in said stem for the handle.

In testimony whereof, I affix my signature, in the presence of two witnesses.

CHARLES MARVIN BROYLES.
